gesellschaft, Stuttgart - Unterturkheim, Ger-
many

Application December 8, 1939, Serial No. 308,232
In Germany November 28, 1938

6 Claims. (Cl. 123—174)

The present invention relates to a system for cooling combustion engines, and more particularly aircraft engines, by evaporation of a cooling liquid.

One object of the invention is to produce a cooling system of this type in which the vaporizer chamber and the recirculating pump are combined into a single constructional unit of small dimensions.

A further object of the invention is to provide a cooling system of the type described, in which the condensate is returned to the vaporizer chamber and a single pump located directly below and communicating with the vaporizer chamber serves to recirculate both the liquid separated during evaporation and the condensate.

Still another object is to produce a cooling system which operates efficiently and reliably and without any appreciable loss of cooling liquid.

These and other objects are accomplished by the arrangement and combination of elements set forth in the following detailed description, defined in the accompanying claims and illustratively exemplified in the accompanying drawings, in which:

Fig. 1 is a substantially diagrammatic illustration of a cooling system according to the invention applied to an aircraft engine.

Fig. 2 is a vertical section through the vaporizer housing and recirculating pump, and

Fig. 3 is a horizontal section taken on line 3—3 of Fig. 2.

Figs. 2 and 3 are on a larger scale than Fig. 1.

In the figures, *a* denotes the vaporizer housing, the upper portion of which constitutes the vaporizer chamber proper; *b* is a high pressure duct connecting the vaporizer chamber with the cooling spaces *c* of the engine *d*. Superheated water or other cooling liquid passes from the cooling spaces *c* through the high pressure duct *b*, to the vaporizer chamber in the housing *a*. The duct *e* connects the lower part of the vaporizer housing *a* with the cooling spaces *c* of the engine *d*. The steam formed in the vaporizer chamber is led through a duct *f* to a condenser *g*, which may be disposed in the tip of a wing *h*. A duct *i* returns the condensate back to the vaporizer chamber.

The pressure duct *b* communicates with the vaporizer chamber in the housing *a* by means of entrance ports *k*. The ports *k* are closed on the inside of the vaporizer chamber by spring flaps *l* which open more or less in response to the pressure prevailing in the high pressure duct *b*. In addition, the flaps *l* influence the direction

of the liquid jets emerging from the ports *k* into the vaporizer chamber *a*. Thus, the ports *k* are self-adjusting and responsive to the pressure prevailing in the cooling system.

5 A pressure pump *m* is arranged in the bottom portion of the vaporizer housing *a*. The pump *m* is driven from the engine *d* through gearing *n*, and its pressure side is connected to the cooling spaces *c* of the engine by means of the duct *e*. A one-way valve *o* is provided in the duct *e* in order to prevent back-flow of the cooling liquid from the cooling spaces *c* to the pump *m*.

The device operates as follows: The cooling liquid in the cooling spaces *c* of the engine *d* is 10 superheated to a temperature exceeding its vaporizing temperature, but, in the cooling spaces and in the high pressure duct *b*, the super-heated liquid is maintained under a pressure preventing its evaporation. In accordance with the pressure 15 prevailing in the pressure duct *b*, the spring flaps *l* uncover the entrance ports *k* into the vaporizer chamber to a greater or less degree, and jets of superheated liquid are discharged into the vaporizer chamber which is approximately under 20 atmospheric pressure.

Owing to the sudden reduction of pressure, the 25 superheated cooling liquid entering the vaporizer chamber separates into vapor and liquid. The vapor flows through the duct *f* to the condenser *g*. The condensate is returned to the vaporizer 30 chamber *a* through the duct *i* by means of a second pump *p*. The liquid separated from the vapor in the upper portion of the vaporizer chamber and the condensate returned to said 35 chamber, both are collected at the bottom of the vaporizer housing *a* and enter the pump *m* at the suction side thereof. From the pump *m*, the entire liquid is recirculated under a pressure of about 4 atmospheres through the one-way valve *o* into the duct *f* and from there to the cooling spaces *c* of the engine *d*.

Instead of providing a second pump *p*, the condensate may be returned to the vaporizer *a* by its own gravity, or the pump *m* may be constructed as a double-acting pump, the suction side of which serves to suck the condensate from the condenser *g* back into the vaporizer chamber. In combustion engines with several rows of cylinders, the ducts connecting the vaporizer housing *a* and the pump *m* with the cooling spaces *c* may be arranged symmetrically in such a manner that corresponding ducts have equal lengths.

We claim:

1. A system for cooling a combustion engine by evaporation, comprising a vaporizer chamber, a

pressure duct to feed superheated cooling liquid to said chamber where it is separated into vapor and liquid, a condenser, a vapor duct connecting said chamber with said condenser, a condensate duct returning the condensate from the condenser to said vaporizer chamber, and a liquid pump disposed immediately below said vaporizer chamber and in direct communication therewith to collect and recirculate both said separated liquid and said condensate.

2. A system for cooling a combustion engine by evaporation, comprising a vaporizer housing and a liquid pump in the bottom portion of said housing, the latter having self-adjusting entrance ports responsive to the pressure prevailing in the cooling spaces of the engine.

3. A system for cooling a combustion engine by evaporation, comprising a vaporizer housing and a liquid pump in the bottom portion of said housing, the latter being provided with entrance ports and having spring flaps normally closing said entrance ports, said spring flaps being adapted to open in response to the pressure prevailing in the cooling spaces of the engine and to influence the direction of the liquid jets emerging from said ports.

4. A system for cooling a combustion engine by evaporation, comprising a vaporizer housing, a recirculating liquid pump in the bottom portion

of said housing, a pressure duct from said liquid pump through the cooling spaces of the engine back to said vaporizer housing, and a one-way valve in said pressure duct to prevent back-flow of cooling liquid from the cooling spaces of the engine.

5. A system for cooling a combustion engine by evaporation, comprising a vaporizer housing, a liquid pump in the bottom portion of said housing, a condenser disposed outside of said housing, a vapor duct leading the vapor formed in said housing to said condenser, and a condensate duct returning the condensate to the suction side of said liquid pump.

10 6. A system for cooling a combustion engine by evaporation, comprising a vaporizer housing, a liquid pump in the bottom portion of said housing, a condenser disposed outside of said housing, a vapor duct leading the vapor formed in said housing to said condenser, a condensate duct returning the condensate to the suction side of said liquid pump, self-adjusting entrance ports in said housing responsive to the pressure prevailing in the cooling spaces of the engine, and a pressure duct to feed superheated cooling liquid to said entrance ports.
